SCREEN FOR WINDOWS

Eric Sigfrid Persson, Malmo, Sweden

Application March 28, 1940, Serial No. 326,458

6 Claims. (Cl. 156—39)

My present invention relates to a screen for windows, and more particularly to screens for windows of the types provided with a frame and a sash which, in opened positions, form between them at least one rectangular opening and at least two triangular openings.

The main object of my invention is to provide a screen of the kind indicated ensuring an adequate engagement between the different screen members to provide for sufficient tightness of the joints between the same.

Another object of my invention is to provide a screen of the kind indicated in which said tightening effect is achieved by very simple means using the screen members themselves for said purpose without any additional parts.

Other objects and characteristics of my present invention will be apparent from the following description having reference to the appended drawing, in which:

Fig. 1 is a diagrammatic view showing the window in opened position,

Fig. 2 shows a perspective view, drawn to an enlarged scale, of the corner marked II in Fig. 1, certain parts being cut away for the sake of clearness,

Fig. 3 shows a similar view, also to an enlarged scale, of the corner marked III in Fig. 1, certain parts being cut away also in this case, and

Fig. 4 shows a partial sectional view of a modified embodiment.

Fig. 5 is a sectional view of the screen roller.

In the embodiment of my invention illustrated in the drawing, a sash 1 is mounted in a frame 2 in such a way that it can be turned about a horizontal axis A—A at about the middle of the height of said sash. The sash 1 is shown opened to a certain extent, the position illustrated corresponding to a maximum ventilation position.

In the top and bottom pieces 2a and 2b of the frame, rollers 3 and 4, respectively, are mounted on which screen members 5 and 6, respectively, are wound. Said rollers 3, 4 are provided with springs 4b between rods 4a and the rollers in the manner well known from common roller blinds. The free edge of each of said screen members 5, 6 is detachably fastened to the sash in any known manner. For instance, said free edge is provided with a bar 7, which is detachably secured to the sash by means of latches 8 of any suitable type.

In order to ensure proper tightness between the frame members 2a, 2b and said rollscreens 5 and 6, respectively, said frame members are each designed so as to provide an edge 10 and

11, respectively, engaged by the screen surface at least when the screen members are unrolled from their rollers to a certain extent.

The upper triangular openings between the frame and sash, and the rollscreen 5, one of which is shown in Fig. 2, are each covered by a screen member 12 positioned at the inside of the window and, in the embodiment shown, comprising a single sheet metal plate of approximately the same shape as the triangular opening to be covered. The screen member 12 can be perforated or not. It can also comprise a netting provided with a frame.

Said plate 12 is provided with a flange 13 having a number of slots 14 of the outline illustrated to enable it to be slid onto buttons 15 in a manner known per se, so as to make it readily detachable from said frame 2.

At the opposite edge said plate 12 is provided with another flange 16 projecting in the opposite direction and thus forming an abutment surface for the sash 1. At the top said plate 12 is provided with a third flange 17 bent so as to form a curve as, for instance, a circle having its centre in or adjacent to the axis of rotation of the sash 1. Said curved flange 17 forms a support for the edge portion of the screen member 5. Since said screen member 5 is subjected to the spring action of the roller 3, it has a tendency to occupy a straightened out position, said tendency being counter-acted by the curved flange 17 forcing said edge portion of the screen member 5 to assume a shape in accordance with the curvature of said flange 17, thus causing the formation of a tight joint between the plate 12 and the screen member 5.

The lower triangular openings are each covered by a similar plate 18, certain features in connection with said plate 18, however, being different from the plate 12. Thus, said plate 18 is provided with a flange 19 corresponding to the flange 13 in respect of its structure but serving to secure the plate 18 not to the frame 2 but to the inside of the sash 1, as shown in Fig. 3.

It is evident, therefore, that said plate 18 will participate in the movements of the sash 1, a slot 20 being provided in the bottom piece 2b of the frame 2 to allow for the passage therethrough of a flange 21 of the plate 18, said flange 21 corresponding to the flange 17 of the plate 12. Another flange 22 corresponding to the flange 16 of plate 12 forms an abutment for engagement with the inside of the frame 2, when the sash is occupying the position illustrated.

It should be obvious then, that the curved

flange 21 coacts with the screen member 6 for achieving the same object as the flange 17 of plate 12. Both plates 12 and 18 can be provided with depressed ridges 23, 24, partly for stiffening the plates, and partly for contacting with the adjacent members of the sash 1 and frame 2, respectively, when the sash is occupying intermediary ventilation positions. Hereby a tightening effect between said parts can be obtained also in said intermediary ventilation positions.

In a modified embodiment shown in a sectional view in Fig. 4 similar ridges 25 are substituted for the flange 19, as far as the tightening action is concerned, the plate 18 is in this case being fastened to the sash 1 by suitable means at the top and the bottom of said plate only.

The embodiments of my invention illustrated and described are intended as exemplifications only and must not in any respect be considered as limitations, since several modifications can be made without departing from the spirit of the invention.

Among said modifications, it may be mentioned that the flanges 17, 21 need not be evenly curved, as shown, but any other shape is included in the protection as long as a satisfactory engagement between the flange and the screen is provided. As regards the screen members 18 and 6, advantage could also be taken of the fact that said plate 18 is lowered, when the window sash is being moved from its closed position towards its maximum ventilation position, since the axis of rotation of the sash lies outside of the inner sash surface to which the plate 18 is secured.

When the sash is to be moved further than to its maximum ventilation position, the screen members will have to be detached. As far as the triangular screen members are concerned, this could be avoided by eliminating the flanges 16 and 22 and securing the plates 12 and 18 to the frame sash, respectively, by means of hinges in connection with springs urging said plates towards the sash and the frame, respectively.

Should it for any reason be desirable, the rollers of the rolls screens can, of course, be mounted in the sash instead of in the frame.

What I claim is:

1. In a window of the type having a sash mounted to pivot in a frame so as to form, in opened positions, at least one rectangular opening and at least two triangular openings between the frame and sash, a roller rotatably mounted in the frame at said rectangular opening, a screen member wound on said roller, means for detachably securing the free edge of said screen member to the sash, means tending to maintain the unrolled portion of said screen member in a strained condition, another screen member at each of said triangular openings, means for detachably securing said last-mentioned screen members to the sash in positions where they cover said triangular openings, slots in the frame for the passage of said last-mentioned screen members, and said last-mentioned screen members engaging the unwound portion of the first-mentioned screen member in a way to force said portion out of its normal extended shape in order to ensure sufficient tightness between the screen members.

2. In a window of the type having a sash mounted to pivot in a frame so as to form, in opened positions, at least one rectangular opening and at least two triangular openings between

the frame and sash, a roller rotatably mounted in the frame at said rectangular opening, a screen member wound on said roller, means for detachably securing the free edge of said screen member to the sash, means tending to maintain the unrolled portion of said screen member in a strained condition, another screen member at each of said triangular openings, means for detachably securing said last-mentioned screen members to the frame in positions where they cover said triangular openings, ridges on the surface of said last-mentioned screen members for engaging the sash, and said last-mentioned screen members engaging the unwound portion of the first-mentioned screen member in a way to force said portion out of its normal extended shape in order to ensure sufficient tightness between the screen members.

3. In a window of the type having a sash mounted to pivot in a frame so as to form, in opened positions, at least one rectangular opening and at least two triangular openings between the frame and sash, a roller rotatably mounted in the frame at said rectangular opening, a screen member wound on said roller, means for detachably securing the free edge of said screen member to the sash, means tending to maintain the unrolled portion of said screen member in a strained condition, another screen member at each of said triangular openings, means for detachably securing said last-mentioned screen members to the sash in positions where they cover said triangular openings, ridges on the surface of said last-mentioned screen members for engaging the sash, and said last-mentioned screen members engaging the unwound portion of the first-mentioned screen member in a way to force said portion out of its normal extended shape in order to ensure sufficient tightness between the screen members.

4. In a window of the type having a sash mounted to pivot in a frame so as to form, in opened positions, at least one rectangular opening and at least two triangular openings between the frame and sash, a roller rotatably mounted in the frame at said rectangular opening, a screen member wound on said roller, means for detachably securing the free edge of said screen member to the sash, means tending to maintain the unrolled portion of said screen member in a strained condition, another screen member at each of said triangular openings, means for detachably securing said last-mentioned screen members to the frame in positions where they cover said triangular openings, flanges on said last-mentioned screen members, and said flanges being curved towards the first-mentioned screen member, so as to force it out of its normal extended shape in order to ensure sufficient tightness between the screen members.

5. In a window of the type having a sash mounted to pivot in a frame so as to form, in opened positions, at least one rectangular opening and at least two triangular openings between the frame and sash, a roller rotatably mounted in the frame at said rectangular opening, a screen member wound on said roller, means for detachably securing the free edge of said screen member to the sash, means tending to maintain the unrolled portion of said screen member in a strained condition, another screen member at each of said triangular openings, means for detachably securing said last-mentioned screen members to the sash in positions where they

cover said triangular openings, flanges on said lastmentioned screen members, and said flanges being curved towards the firstmentioned screen member, so as to force it out of its normal extended shape in order to ensure sufficient tightness between the screen members.

6. In a window of the type having a sash member mounted to pivot in a frame member so as to form, in opened positions, at least one rectangular opening and at least two triangular openings between the frame and sash, a roller rotatably mounted on the frame at said rectangu-

lar opening, a screen member wound on said roller, means for detachably securing the free edge of said screen member to the sash, means tending to maintain the unrolled portion of said screen member in a strained condition, another screen member at each of said triangular openings, means for detachably securing said last mentioned screen members to one of the contiguous window members in positions where they cover said triangular openings.

ERIC SIGFRID PERSSON.
